(57) CLAIM

The ornamental design for a chair as shown and described.

DESCRIPTION

FIG. 1 is a perspective view of a first embodiment of a chair showing my new design.

FIG. 2 is a front elevation view thereof.

FIG. 3 is a right side elevation view thereof.

FIG. 4 is a rear elevation view thereof.

FIG. 5 is a left side elevation view thereof.

FIG. 6 is a top plan view thereof; and,

FIG. 7 is a bottom plan view thereof.

The dashed lines shown in the drawings are for purposes of illustrating portions of the chair that form no part of the claimed design.

1 Claim, 7 Drawing Sheets
